United States Patent Office.

GEORGE C. MILLER, OF GOSHEN, AND JOSEPH H. COATES, OF NEW YORK, N.Y.

Letters Patent No. 100,782, dated March 15, 1870.

IMPROVEMENT IN BASINS WITH WASTE-PIPE ATTACHMENTS.

The Schedule referred to in these Letters Patent and making part of the same.

We, GEORGE C. MILLER, of Goshen, in the county of Orange, and State of New York, and JOSEPH H. COATES, of the city, county, and State of New York, have invented certain Improvements in Sanitary Basins, of which the following is a specification.

Nature and Objects of the Invention.

This invention relates to that class of basins which have a waste-pipe attached to them, such, for example, as wash-basins, urinals, and sinks; and

The invention consists in the construction, herein-after described, of that portion of the basin to which the pipe is connected, and also in the combination therewith of a coupling-sleeve adapted to fit upon the upper and flaring end of the lead-pipe, and couple it firmly to the basin.

Description of the Accompanying Drawings.

Figure 1 is a bottom view of a wash-basin, with the coupling-sleeve and the lead-pipe attached, as they would be when set in position.

Figure 2 is a vertical section, in detail, showing the construction of the extreme lower portion of the basin for the purpose of attaching the waste-pipe.

Figure 3 is a vertical central section of the parts shown in fig. 1.

General Description.

A is a wash-basin, constructed according to my improvement:

The basin here shown is provided with an overflow, *a*, which is made with and forms a part of the basin, and though this overflow is preferred it is still no necessary condition of the invention, but the common overflow may be used, if desired.

The basin A is formed at the bottom with a couple of lugs, *b*, which are here shown as made with a slight inclination on the upper surface of that part which connects with the sleeve, so as to draw the sleeve up more

firmly, though this inclination may be dispensed with, and this upper surface may be made horizontal.

The basin is also formed with the usual downward projection *c*, which enters the waste-pipe.

B is the waste-pipe, which is enlarged at the top in the usual way, as shown.

C is a sleeve, properly formed to receive the funnel-shaped end of the waste-pipe, and it is also provided with lugs or projections *d d*, which interlock with the lugs *b*, and draw the upper end of the waste-pipe upward, and sustain it in position, by means of the sleeve *C*, which also compresses the waste-pipe inward around the part *c* of the basin.

To prevent leakage, in the case of a stoppage of the pipe below, a putty joint may be made, in the usual way; but we prefer to secure this object by the introduction of an India-rubber ring, *D*, between the upper end of the waste-pipe and the tube *c*, which ring is easily applied, fully answers the purpose, and is more convenient in case it should be desirable, for any purpose, to disconnect the basin from the waste-pipe.

It is obvious that the form of the lugs *b* may be changed, and may be even made to project outwardly, instead of inwardly, and the lugs *d* correspondingly changed to connect with them, without changing the principle of the invention.

Claims.

We claim as our invention—

1. The basin A, with the projections or lugs *b* upon its lower portion, as set forth.
2. The combination with the basin A, as set forth, of the sleeve *C*, substantially as described.

GEO. C. MILLER.
JOS. H. COATES.
